COUNTER MECHANISM

William L. Tancred, Hartford, Conn., assignor to
Veeder-Root Incorporated, a corporation of
Connecticut

Application December 2, 1937, Serial No. 177,721

7 Claims. (Cl. 235—132)

This invention relates to counter mechanisms.

It has among its objects to provide an improved counter mechanism for use with dispensing apparatus; and particularly such an improved mechanism having improved means for interrupting the dispensing operation when a predetermined count has been reached.

A further object of this invention is to provide an improved predetermined mechanism successively operative at predetermined points in a counting operation.

A still further object is to provide an improved predetermined counter mechanism having improved controlling means for the counter drive, and more particularly such means adapted to interrupt the drive at predetermined intervals and adapted to be manually reestablished and continue the count.

Still another object is to provide an improved mechanism of this type having improved controlling means automatically operating with a snap action and controlling the circuit of the counter driving motor.

A yet further object is to provide an improved predetermined counter mechanism of the resettable type, especially adapted for use with a motor driven dispensing device for insuring that the circuit of the motor will be open during the resetting operation. These and other objects of the invention will hereinafter more fully appear.

In the accompanying drawing, one form of the invention is shown for purposes of illustration.

In this drawing:

Figure 1 is a side elevation of part of a gasoline dispensing computer equipped with these improvements, only one of the quantity counters together with its counting and resetting drive trains being shown and the controlled switch being shown in open position;

Fig. 2 is a plan view of the structure of Figure 1;

Fig. 3 is a detail view of the predetermined mechanism of Figure 1 with the switch in closed position;

Fig. 4 is an enlarged sectional view, taken on line 4—4 of Figure 2, showing parts of the predetermined mechanism and also showing the cooperating elements of the counter resetting mechanism;

Fig. 5 is a similar view showing the parts in an intermediate position;

Fig. 6 is a detail sectional view on line 6—6 of Figure 4;

Fig. 7 is a perspective view partly in section showing the spring connection between the indexing wheel and the highest counter wheel, and

Fig. 8 is a simplified, somewhat diagrammatic view of a gasoline dispensing pump with these improvements.

In this drawing, the improved predetermined mechanism is illustrated in connection with one

of the quantity, or gallons, counters A in a well known gasoline dispensing computer, the fractional gallons wheel 1a of which has a gear 1 fixed thereto which is driven through a train of gears 2, 3, 4 and 5 from a shaft 6 and connected to the usual fluid meter 6a which receives fluid from a usual pump 6b, driven by the usual electric motor 6c. The lowest order wheel 1a is operatively connected with units wheel 7 of the counter by usual locking transfer mechanism including the intermediate pinion 8, and the tens wheel 9 is similarly connected to the units wheel 7, whereby by the rotations of each lower order wheel are transferred to the next higher order wheel in the usual manner; the several counter wheels being freely rotatable on an axial shaft 10, herein a supporting and resetting shaft, journaled in the side frames 11 and 12 for purposes hereinafter described in connection with resetting of the counter.

In accordance with the present invention, improved predetermined counter mechanism associated with the tens wheel 9 of the counter A is provided for controlling an electric switch 13 in the circuit 14 of motor 6c. As in a usual construction, a transverse shaft 15 is journaled in the side frames 11 and 12 parallel to the shaft 10, on which the gear 2 of the counter driving train is journaled. This shaft has a collar 16 pinned to its other end carrying a horizontally extended switch actuating arm 17 which is pivotally connected by a rod 18 to a link 19 of the switch 13, herein shown as a toggle type switch, the other link 20 of which is pivoted to link 19 at the fixed center 21 and carries the spaced movable contacts 22 which cooperate with the stationary spaced contacts 23. A spring 24 is provided to connect the links 19 and 20 across the pivot 21, relative to which the links 19 and 20 are adapted to occupy positions disposing the spring on opposite sides of the center 21, as shown in Figures 1 and 3 in the open and closed positions of the switch.

The improved predetermined mechanism for controlling the switch actuating arm 17 comprises an indexing lever 25, fixed to a hub 26 which is pinned to the shaft 15 on the opposite side of the side frame 12 from the switch actuating arm 17, the arm 17 and the indexing lever 25 being movable in unison with the shaft 15. The indexing lever 25 carries, at its free end, a fixed pin or stud 27, herein having a flat face 27a. The stud 27 cooperates with the teeth, or cams, 28 of an indexing wheel 29 journaled on the reduced portion of a collar 31 which is pinned to the counter resetting shaft 10, the indexing wheel 29 being provided with ten teeth 28 corresponding to the numeral positions on the tens wheel 9, each having an inclined cam face 28a and an angularly related radial face 28b.

In the normal position of the parts, in which the switch actuating lever 17 is horizontally disposed (Fig. 3), the indexing stud 27 is disposed in the bottom of the V-shaped notch 32 between adjacent teeth 28, which limits the movement of the indexing arm 25 and consequently limits the movement of the switch 13 in the closing movement of the latter under the action of spring 24. The indexing arm 25 also has a projection 33 at its free end providing an abutment for engaging the transfer pinion shaft 34 journaled in the side frame 12 and acting as an abutment for limiting the movement of the indexing arm and the switch 13 as the latter is moved to open position under the action of its spring 24.

The indexing wheel 29 is operatively connected with the tens order wheel 9 by a pin and slot connection comprising the headed pin 35 fixed in a plate 36 carried by the number wheel 9. The pin 35 is extended through an arcuate slot 37 in the indexing wheel 29 with its head 38 spaced from the outer face of the indexing wheel to receive one hooked end of a C-shaped spring 40, the other end of which has its oppositely hooked portion 41 engaged with a pin 42 fixed in the indexing wheel 29 adjacent the slot 37.

It will thus be evident that when the tens wheel 9 is rotated a tenth of a revolution by the transfer pinion 8 to indicate that ten gallons have been dispensed, this movement is transmitted in the same direction to the indexing wheel 29 through the resilient connection provided by the spring 40. During this movement of the indexing wheel 29, the indexing arm 25 and the switch actuating arm 17 are rotated in a counter-clockwise direction, as viewed in Figure 3, by the camming action of the inclined portion 28a of the adjacent tooth 28 on the indexing wheel 29, until the indexing arm reaches the position shown in Figure 5 in which the spring 24 of switch 13 has reached an over-center position. As the switch moves from its closed position, shown in Figure 3, into its open position, shown in Figure 1, under the action of spring 24, the indexing arm 25 is moved into the position shown in Figure 1 in which its abutment 33 is in engagement with shaft 34. As the stud 27 leaves the inclined portion 28a of the indexing wheel 29, the latter is moved ahead, under the action of the stressed spring 40, to bring the next notch 32 into position under the stud 27. It will be noted that in this position of the parts, the stud 27 is out of the path of the teeth 28 of the indexing wheel. The circuit to the motor 6c now being interrupted, the parts will remain in this position and no more gasoline can be dispensed until the operator manually closes the switch 13 by depressing the switch handle 44 to move the parts into the position shown in Figure 3.

Means are also provided for resetting the counter wheels of counter A in a usual manner. Herein, the resetting means includes a transverse resetting shaft 45, journaled in the side frames 11 and 12 directly above a shaft 45a of the counter drive, coaxial with the counter driving gears 3 and 4, and having operative connections 46 at both ends adapted to receive a reset operating wing nut. The shaft 45 has a gear 47 fixed thereto just outside the side frame 11, which meshes with a gear 48 fixed to shaft 45a. The gear 48 has connected therewith a gear 49 which meshes with an intermediate gear 50 journaled on shaft 15 which, in turn, meshes with a gear 51, angularly adjustably fixed to the axial resetting shaft 10 of the counter A. The shaft 10 is provided

with the usual longitudinal resetting groove 52 which is adapted to cooperate with resetting pawls 53 in the several counter wheels, one of which is shown in Figure 4. It will be understood that when the shaft 45 is rotated to rotate the axial shaft 10 in the proper direction, herein the counting direction, each of the counting wheels 1a, 7 and 9 will be picked up by its resetting pawl 53 and rotated in a counting direction to zero; a clutch connected element 53a, fixed to shaft 45a, 10 then slipping in a well known manner relative to a cooperating clutch element 53b carried by the gear 4.

As shown herein, the predetermined counter of this invention is designed to operate the switch 13 to open the motor circuit 6c whenever 10 gallons have been dispensed or, in the case of a dispensing operation involving more than ten gallons, to open the switch upon reaching any multiple of ten gallons, as, for example, at ten 20 gallons, twenty gallons, thirty gallons, and so forth. Assuming that the counter A has been reset to zero, and the switch 13 has been closed by manually depressing the switch handle 44, the predetermined mechanism will be in the position 25 shown in Figure 3 and the switch 13 being closed, will permit pump 6b to be operated. As gasoline is dispensed, the fractional wheel 1a will be rotated by the meter drive including the shaft 6, bevel gears 4 and 5, and the drive train including 30 gears 3, 2 and 1, the rotation of this lowest order wheel 1a being transferred to the units wheel 7 through the transfer mechanism, and from the units wheel 7 through the transfer mechanism to the tens wheel 9, in the usual manner. As transfer takes place from the units wheel 1 to the tens wheel 9 to rotate the latter from its zero position to its 1 position, thus indicating that ten gallons have been dispensed, the plate 36, carried by tens wheel 9, will be rotated in a counter-clockwise direction as viewed in Figure 3 and will move the pin 35 upwardly in the slot 37 to stress the spring 40. When the parts have reached the position shown in Figure 5, the spring 24, which has now passed into an over-center position, acts on the indexing arm 25 through the linkage described to move this arm with a snap action into the position shown in Figure 1 which corresponds to the open position of switch 13.

If the operator wishes to dispense more than ten gallons, he can manually depress the handle 44 to close the motor switch 13, when the stud 27 will enter the next notch 32 on the indexing wheel 29 which will permit another ten gallons to be dispensed. It will be noted that during the switch closing movement, due to the flat face 27a of stud 27 and the radial face 28b of the adjacent tooth on indexing wheel 29, the stud is able to move into the bottom of notch 32 without moving the number wheel 9. When the total amount dispensed reaches 20 gallons, the indexing wheel 29 will again trip out the switch 13, as described above, and the operator will again manually close the switch if he wishes to continue dispensing. The dispensing operation can be continued indefinitely 65 as long as the operator manually closes the switch 13 following each ten gallon increment dispensed.

Following a dispensing operation and prior to the next sale, the operator resets the counter A by rotating the shaft 45 by either of the operative connections 46. If the amount dispensed was ten gallons or any multiple of ten gallons, the indexing arm 25 will, following dispensing, be in the switch open position shown in Figure 1 in which its stud 27 is out of contact with the indexing 75

wheel 29. If the amount dispensed should be less than ten gallons or less than some multiple of ten gallons, the predetermining mechanism, following dispensing, will occupy the position shown in Figure 3. In this case, upon picking up the tens order wheel 9 by the rotation of the counter resetting shaft 10, the stud 27 will be cammed out of the notch 32 upon the initial rotation of the number wheel 9 in a resetting direction, thus immediately to trip the switch 13 and cause the same to move to its open position, shown in Figure 1, in which the indexing arm 25 with the stud 27 are out of the path of the indexing wheel 29.

As a result of the present invention, it will be evident that a simple and effective predetermining mechanism has been provided for interrupting the motor circuit of a liquid dispensing device following the dispensing of a predetermined quantity of liquid. Further, it will be noted that, by reason of the improved construction, the motor circuit is also automatically interrupted in the resetting movement of the counter, if it has not already been interrupted automatically by reason of the operation resulting from the quantity of liquid dispensed. Further, the advantage of this device to the operator will be apparent where even ten gallon quantities are to be dispensed. Further, the value of this invention in connection with gasoline dispensing apparatus will be evident when it is considered that, by reason of the automatic interruption of the dispensing operation at regular intervals, it is impossible for a large amount of gasoline to be accidentally discharged outside the tank of a vehicle so as to cause a serious fire risk.

While I have in this application specifically described one embodiment which my invention may assume in practice, it will be understood that the same is shown for purposes of illustration and that the invention may be modified and embodied in various other forms without departing from the spirit or the scope of the appended claims.

What I claim as new and desire to secure by Letters Patent is:

1. In combination, a counter having a rotatable number wheel, predetermining mechanism associated therewith including a cam member rotatable with said number wheel and having a lost motion connection therewith and a cam follower cooperating with said cam member, said cam member having a plurality of cams thereon corresponding to numeral positions on said number wheel, said cam follower being successively operable to inoperative position by the cams on said cam member during counting, and means for manually repositioning said cam follower following operation thereof by one of the cams of said cam member.

2. A predetermined counter including a plurality of operatively connected number wheels, means for driving the lowest order wheel, predetermining mechanism associated with the highest order wheel including a cam member rotatable therewith having a series of cams corresponding to numeral positions on said wheel and a cam follower successively operative by said cams during a counting operation, and means for reconditioning said predetermining mechanism following the successive operations thereof, said cam member having a resilient lost motion connection with said highest order wheel.

3. A predetermined counter including a plurality of operatively connected number wheels, means for driving the lowest order wheel, pred-

termining mechanism associated with the highest order wheel including a cam member rotatable with the latter wheel having a series of cams thereon corresponding to numeral positions on said wheel and a cam follower successively operative by said cams during a counting operation, and means for reconditioning said predetermining mechanism following each successive operation thereof, said cam member having a resilient lost motion connection with said highest order wheel, and said cam follower being biased from an on-center position either into engagement with said cam member when between adjacent cams thereon, or wholly out of engagement therewith following an operation thereby.

4. A predetermined counter including a plurality of operatively connected number wheels, means for driving the lowest order wheel, predetermining mechanism associated with the highest order wheel including a cam member rotatable with the latter wheel having a series of cams thereon corresponding to numeral positions on said wheel and a cam follower operated successively by said cams during a counting operation, means for reconditioning said predetermining mechanism following each successive operation thereof, said cam member having a resilient lost motion connection with said highest order wheel, and said cam follower being biased from an on-center position either into engagement with said cam member when between adjacent cams thereon, or out of engagement therewith following operation thereby, and means for limiting the movement of said cam follower in its movement away from said cam member.

5. In a counter, a numeral wheel, a predetermining mechanism associated with said numeral wheel and including a cam member rotatable therewith, a cam follower adapted to be operated by said cam during a counting operation, said cam member having a resilient lost motion connection with said numeral wheel.

6. In a counter, a numeral wheel, predetermining mechanism associated with said numeral wheel and including a cam member rotatable with the latter wheel, and a cam follower operated by said cam during a counting operation, said cam having a resilient lost motion connection with said numeral wheel, and said cam follower being biased from a non-center position either into engagement with said cam member or wholly out of engagement therewith following an operation thereby.

7. In a counter, a numeral wheel, a shaft on which said wheel is rotatably mounted, predetermining mechanism associated with said wheel and including a cam member having a series of cams rotatably mounted on said shaft, means connecting said cam to said wheel for simultaneous rotation therewith and including a pin on said wheel adapted to extend through an elongated slot in said cam, spring means for normally urging said cam to position said pin in one end of the slot, and a cam follower retarding rotation of said cam member and operated by said cam toward an inoperative position during a counter operation, spring means for moving said follower out of engagement with said cam following a predetermined rotation thereof, whereby said cam spring means will advance said cam to its normal position relative to the numeral wheel.

WILLIAM L. TANCRED.
